UNITED STATES PATENT OFFICE.

GEORGE GODDU, OF WINCHESTER, AND FRED LUTHER MACKENZIE, OF BEVERLY, MASSACHUSETTS, ASSIGNEES TO UNITED SHOE MACHINERY CORPORATION, OF PATERSON, NEW JERSEY, A CORPORATION OF NEW JERSEY.

MACHINE FOR OPERATING ON SHOE STOCK.

Application filed October 24, 1918. Serial No. 259,569.

To all whom it may concern:

Be it known the we, GEORGE GODDU and FRED L. MACKENZIE, citizens of the United States, residing at Winchester, in the county of Middlesex and Commonwealth of Massachusetts, and Beverly, in the county of Essex and Commonwealth of Massachusetts, respectively, have invented certain Improvements in Machines for Operating on Shoe Stock, of which the following description, in connection with the accompanying drawings, is a specification, like reference characters on the drawings indicating like parts in the several figures.

15 This invention relates to operations performed upon shoe stock and especially to the making of incisions in the work operated upon.

The invention by way of example is herein 20 illustrated in connection with a fastening inserting machine designed for securing a welt to an upper and insole, the particular machine shown being of the type of that disclosed in United States Patent No. 1,401,247, 25 granted Dec. 37, 1921, on an application of George Goddu and Fred L. MacKenzie, certain features of which are claimed in United States Patent No. 1,410,694, granted March 28, 1922, on an application of Fred L. Mac-

30 Kenzie.

While the invention is herein described in connection with the nailing of a welt to a shoe, this is primarily for purposes of illustration, the invention, in some of its phases, 35 being applicable to operations performed upon stock other than welting, and to fastening other than by nails.

In the operation of fastening inserting machines of such type, a welt strip is attached to the margin of an upper and insole beginning on one side of the shoe usually at a point adjacent to the breast edge of the heel when applied to the shoe, continuing about the forepart of the shoe, and ending 45 at a point adjacent to the breast edge of the heel on the other side of the shoe. The machine severs nails from a nail string and inserts them progressively into the welt concurrently with the guiding of the welt on to the shoe. The welt is located on the shoe 50 with its outer edge parallel with the contour

line of the upper and insole. Consequently, it will be curved in its own plane at points where the contour of the shoe is curved, such, for example, as at the base of the ball 55 portion of the shoe where the ball portion merges into the shank. The curving of the welt compresses its inner edge causing the inner edge to rise with the possible formation of puckers or folds therein. When the 60 outsole is applied to the shoe the upstanding or puckered portion of the welt is forced down upon the upper and insole so that the ultimate result of the formation of such 65 folds or puckers in the welt is to thicken it by reason of which it will not bend easily thereby detracting from the flexibility of the shoe.

This invention accordingly contemplates 70 the incising of the welt as it is applied to the lasted upper in such portions thereof as depart to any great extent from a straight line. In certain aspects of the invention and for some purposes, the incisions need not be of the form illustrated, since under 75 some circumstances other forms than that shown may be desirable, that which will be most desirable in any particular instance depending upon the type of shoe being manufactured and other obvious considerations. 80

In its method aspect the invention contemplates the incision of the welt as it is applied to a shoe in predetermined relation to points at which fastenings are inserted to attach the welt to the shoe. 85

In order that none of the nails used by the illustrated machine (which embodies a preferred form of mechanism which may be utilized to carry out the improved method and constitutes an embodiment of the invention in its machine aspect) to attach the welt shall enter the incisions and thus be ineffective to secure the welt to the upper and insole, the invention contemplates so controlling the incising operation that it is performed upon a portion of the welt in predetermined relation to the points at which nails are to be driven. Preferably the incising means is controlled by the operator so that it can be made operative or inoperative 100 at will. It can accordingly be controlled so as to make incisions in any necessary part 95

of the welt to assist the welt to lie flat and increase its flexibility.

Although the incising means has been hereinbefore described in connection with a string nailing machine, it is nevertheless recognized that its utility is not limited to use in connection with a machine of that type but it may be used in connection with machines of other types, particularly those which may be employed for attaching welts to other pieces of shoe stock or in connection with the attachment of shoe parts other than welts.

An important feature of the invention in relation to its incorporation in fastening inserting machines resides in the provision of a frame upon which is mounted fastening inserting mechanism carried by a laterally movable head with which is also associated means for making incisions in the work during the insertion of fastenings therein. Preferably, and as illustrated, the fastening inserting mechanism comprises a driver and an awl which are operated in directions to engage the work and also to feed the work. The incising means is preferably mounted for sliding movement on the awl bar and is operated from the driver bar in such a manner that when such bar is lowered to insert a fastening into the work, the incising means is also operated to make an incision in the work adjacent to the point where the fastening is inserted.

Although the incising means has been herein described as associated with a fastening inserting machine, nevertheless, such means may be used in machines other than fastening inserting machines or may constitute in itself a separate machine.

Moreover, although the invention is particularly intended for operation on welts, it is realized that either the invention as a whole or certain features thereof may be usefully employed on work of other kinds.

Other objects and features of the invention will appear as the description proceeds and will be pointed out in the appended claims.

In the drawings;

Fig. 1 is a view in front elevation of a fastening inserting machine embodying the invention;

Fig. 2 is a view in perspective of the fastening inserting instrumentalities and the incising means looking from the upper left-hand side in Fig. 1;

Fig. 3 is an enlarged view in front elevation showing parts of the fastening inserting instrumentalities and the incising means and with the incising means connected to its operating means;

Fig. 4 is a view from the rear of certain elements of the connections between the incising means and its operating means.

Fig. 5 shows the arrangement of the incising blade relatively to the throat, v.t

guide, and awl bar upon the latter of which the incising means is slidably mounted, and

Fig. 6 illustrates a shoe to which a welt has been attached by the use of the invention.

The machine in connection with which the invention is herein shown comprises a column 2 upon which is mounted a fixed head 4 on the front end of which a head 6 is supported in such manner as to be movable laterally of the fixed head 4. In machines of the type illustrated, the movable head is mounted for swinging movement between the fixed head 4 and plates 8 and 10 secured thereto.

The movable head 6 carries the fastening inserting mechanism and also the means for making incisions in the work in which the fastenings are inserted. Such mechanism comprises a driver 12 for forcing the fastenings into the work, a driver bar 13, a nail string guide 14, a knife carrying arm 16 and an awl bar 18 carrying an awl adapted for projection into the work.

After the penetration of the work by the awl, the head 6 is swung to the left so as to feed the work, which, while being operated upon by the fastening inserting mechanism is upheld by a horn 20 or other suitable work support. Upon completion of the movement of the head 6 to the left, the awl is retracted from the work, and the head 6 is swung back to the right thereby bringing the driver into alignment with the opening made in the work by the awl. Thereafter, the driver is moved downwardly to effect the driving of the nail which meanwhile has been severed by the knife from the nail string in the guide 14.

The driver and awl are guided in the passages of a throat 22 carried by the lower end of the swinging head 6 and movable therewith relatively to the guard plate 24 which positions the work during operation thereon by the fastening inserting mechanism and is formed with an elongated opening 26 in which the throat 22 moves. The guard plate 24 is further provided with devices in which is formed a passage 28 adapted to receive the welt to be operated upon and to guide the same beneath the throat 22 in position for the insertion of fastenings therein. The elements thus far described form in themselves no part of the present invention but are set forth in the said Patent No. 1,401,247, to which reference has heretofore been made.

For slitting or cutting the inner edge of the welt, when desired, an incising blade or cutter 30 is slidably mounted in the throat 22, being reciprocated therein by a holder 31 sleeved on the awl bar 18 and provided at its upper end with upper and lower spaced lugs or projections 32 and 34 respectively.

Preferably, and as illustrated, the incis-

ing blade 30 is operated by connections with the driver bar so as to coordinate its movements with those of said bar. Accordingly, a stud 37 extending outwardly from the driver bar is received in a cam shaped slot 38 of a lever 40, the other end of which is operatively connected to the lugs 32 and 34 of the incising blade 30.

Such connections comprise a stud 42 mounted in a bracket 44 in turn carried by the swinging head 6. The stud 42 serves as a fulcrum for the lever 40 which at its lower end has formed therewith or secured thereto a bar 46 which is recessed to serve 15 as a guideway for a sliding member 48. The member 48 has at its end a boss 50 adapted to be interposed between the lugs 32 and 34 of the incising means, movement of the member 48 relative to the stud 42 being permitted by the slot 51 in said member. When the bar 46 has been moved to introduce the boss 50 into the space between the lugs 32 and 34, the motions of the lever 40 are communicated to the incising means. 25 When, however, the member 48 has been so moved as to withdraw the boss 50 from between the lugs 32 and 34, the incising means is not operated since movement of the lever 40 about its fulcrum 42 as the driver moves 30 up and down no longer affects the lugs 32 and 34 of the incising means.

Preferably, the operator is enabled to render the incising means operative or inoperative at will. Accordingly, we provide 35 manually controllable means for engaging or disengaging the boss 50 from the lugs 32 and 34. In the illustrated construction, such means comprises a lever 52 carried by the stud 42 and operable by a handle 54 to move its cam surface 56 either into or out 40 of engagement with a stud, or the like, 58 projecting from the member 48 into the path of movement of the cam lever. The member 48 is moved in a direction opposite 45 to that in which it is moved by the cam lever 52 by a spring 60. Referring to Fig. 3, it will be seen that when the stud 58 of the member 48 engages with the upper part of 50 the cam surface of the lever 52, the spring 60 is enabled to move the member 48 far enough to the left to insert the boss 50 of 55 said member between the lugs 32 and 34 of the incising means. When, however, the cam lever 52 is moved from the position 60 shown in Fig. 3 to that shown in Fig. 1, the cam surface of the lever 52 operates against the stud 58 of member 48 and withdraws the boss 50 of said member from 65 between the lugs 32 and 34, thus breaking the connection between the lever 40 and the incising means as indicated in Fig. 1. It is 70 desirable that the incising means when free from the control of the member 48 should occupy a certain normal position. To this end a spring 62 is provided which normally

urges such means upwardly to a point determined by the engagement of the upper surface of the upper lug 32 with a part of the swinging head 6.

The formation of the lower lug 34 of the 70 incising means of less width than the upper lug 32 renders it easy to engage or disengage the boss 50 of the member 48 from the lugs 32 and 34. The projection of lug 32 lying to the right of the corresponding surface of lug 34 constitutes a guide for the head of the boss 50 thus facilitating the introduction of the head of the boss into the space between the lugs. 75

If the handle lever 54 is operated during 80 the movement of the blade 30 downwardly to withdraw the boss 50 from between the lugs 32 and 34, the blade will at once cease to move downwards and will begin to move upwards under the impulse of the spring 62. When, on the other hand, the handle 54 is turned in a direction to occasion engagement of the boss 50 between the lugs 32 and 85 34 when the driver is at or near the extremity of its downward movement, the boss will not at once move into the space between the lugs 32 and 34 inasmuch as in such position of the driver, the boss is aligned with the lower lug 34 (see Fig. 2). As the driver rises, however, it turns the 90 lever 40 about stud 42 until the boss is brought into alignment with the space between the lugs 32 and 34 whereupon the spring 60 thrusts the boss into such space, 95 thus operatively connecting the incising means with the lever 40. 100

The mounting of the cutter holder 31 upon the awl bar 18 insures the cutting of the welt in positions which will not interfere with the subsequent attachment of the 105 welt to the shoe by the nails which are driven for this purpose. The distance from the awl to the cutter is less than, and is illustrated as approximately half, the distance between adjacent awl holes and thus the cuts are similarly spaced with respect to the nails when they are driven. This formation of the slits or incisions in the welt in predetermined relation to the positions at which the fastenings are inserted is believed 110 to be new with applicants and constitutes an important feature of the present invention, whether the invention is viewed from its method or from its machine aspect. 115

This invention as applied to the attachment of a welt to a shoe by a machine of the type illustrated contemplates particularly the actuation of the lever 54 by the operator at such times as to cause a number of incisions to be made in the welt on both sides 120 of the shoe, those on either side of the shoe being disposed half on one side of the break line or ball line of the shoe and half on the other, see line ω — ω , Fig. 6. For the reasons hereinbefore set forth, such incisions greatly 125 130

enhance the flexibility of the shoe at the ball line, or, in other words, at the base of the ball portion of the shoe.

Having fully described my invention, 5 what I claim as new and desire to secure by Letters Patent of the United States is:

1. In a machine of the class described, the combination of a cutter for slitting shoe stock and means for inserting string nails 10 into the stock comprising an awl and means for operating the awl to penetrate and feed the stock intermediate between the operations of the cutter.

2. In a machine of the class described, 15 the combination of means for slitting shoe stock and means for feeding the stock relatively to the slitting means comprising an awl and means for operating the awl to penetrate and feed the stock.

3. In a machine of the class described, 20 the combination of a frame, a head movable laterally on the frame, a cutter carried by the head for slitting shoe stock, and means also carried by the head for feeding the stock relatively to the cutter.

4. In a machine of the class described, 25 a frame, fastening inserting mechanism comprising a head laterally movable on the frame, and a cutter carried by the head for making incisions in the work during the insertion of the fastenings therein.

5. In a machine of the class described, 30 a frame, a head laterally movable on the frame, a driver carried by the head, means for feeding the work, and means carried by the head for making incisions in the work.

6. In a fastening inserting machine, a 35 laterally movable head, a driver carried by the head, means carried by the head for feeding the work, and other means carried by the head for making incisions in the work.

7. In a fastening inserting machine, a 40 swinging head, a throat carried by the swinging head and having passages to receive a driver and an awl, means for operating the driver, awl and swinging head in such a manner as to insert fastenings progressively in a piece of shoe stock, and means for making incisions in the piece of shoe stock concurrently with the insertion of the fastenings in the shoe stock.

8. In a fastening inserting machine, a 45 swinging head, a throat carried by the swinging head and having passages to receive a driver and an awl, means for operating the driver, awl and swinging head in such a manner as to insert fastenings progressively in a piece of shoe stock, and a cutter carried by the swinging head and movable through a passage of said throat for making incisions in the piece of shoe stock concurrently with the insertion of fastenings therein.

9. In a fastening inserting machine,

means for inserting fastenings comprising a laterally movable head carrying a throat provided with passages to receive a driver and an awl, means for operating said driver, awl, and movable head to insert fastenings progressively into a piece of shoe stock, a guard plate by which the work is positioned for operation thereon by the fastening inserting mechanism and which is provided with a passage in which the throat moves during the insertion of fastenings in the shoe stock and with a second passage adapted to receive a welt and to guide the welt beneath the throat of the movable head in position for the insertion of fastenings therein, and means carried by said head and movable relatively to said throat for making incisions in the welt as it is being attached to the stock.

10. In a machine of the class described, 50 in combination, means for inserting fastenings comprising a driver and an awl, means for operating the driver and awl in directions to engage the work and also to feed the work, and means for making incisions in the work during operation on the work by the driver and awl and intermediate between the points of operation of the driver and awl on the work.

11. In a machine of the class described, 55 means for inserting metallic fastenings comprising a driver and a driver bar and means operatively connected with the driver bar for making incisions in the work during the insertion of fastenings in the work.

12. In a machine of the class described, 60 means for inserting fastenings comprising a driver and a driver bar, a cutter operatively connected with the driver bar for making incisions in the work during the insertion of fastenings therein, and means operable at the will of the operator for controlling the operation of the cutter.

13. In a machine of the class described, 65 means for inserting fastenings comprising a driver and a driver bar, means for making incisions in the work during the insertion of fastenings therein, a lever operatively connected to the driver bar, connections between said lever and said incising means, and means operable at the will of the operator to make or break said connections.

14. In a machine of the class described, 70 means for inserting fastenings comprising a driver and a driver bar, means operatively connected with the driver bar for making incisions in the work during the insertion of fastenings therein, such connections comprising a part connected to the incising means, a lever operatively connected with the driver bar, and a member carried by said lever operable into and out of operative relation with said part.

15. In a machine of the class described, 75 means for inserting fastenings in a piece of

work comprising an awl bar, a cutter slidably mounted on the awl bar for making incisions in the work during operation thereon by the fastening inserting means, and means 5 for operating said cutter.

16. In a machine of the class described, means for inserting fastenings in a piece of work comprising a driver, a driver bar, and an awl bar, incising means slidably mounted 10 on the awl bar, and means operatively connected with the driver bar for operating said incising means.

17. In a machine of the class described, means for making incisions in a piece of 15 work, and operating means for the incising means comprising a lever, an actuator mounted for longitudinal sliding movement relatively to the lever, and means controllable at the will of the operator for moving said actuator longitudinally into or out of operative 20 relation to the incising means.

18. In a machine of the class described, means for making incisions in a piece of work formed to provide a recess, means for 25 operating the incising means comprising a lever, a member slidably mounted in said lever for movement into and out of said recess, and means controllable at will for moving 30 said member into or out of said recess.

19. In a machine of the class described, means for making incisions in a piece of work having a part connected therewith, means for operating the incising means comprising a lever, a member slidably mounted 35 in the lower end of the lever for movement into and out of operative relation with the part on the incising means, means for moving said member comprising a lever having a cam surface, a part connected with said member and operable by said lever to effect movement of the member in one direction, and a 40 spring for moving the member in a direction opposite to that in which it is moved by said lever.

20. In a machine of the class described, means for making incisions in shoe stock having a part projecting therefrom, means for operating said incising means comprising a lever having a stud mounted therein, 45 a member slidably mounted in the lever and provided with a slot embracing said stud thus permitting movement of said member relatively to said lever, a projection 50 on said member, a cam lever connected to said stud and operable against said projec-

tion to move said member out of engagement with the part on said incising means, and yielding means for moving said member into engagement with said part.

21. In a machine of the class described, 60 means for inserting fastenings comprising a driver and an awl bar, means slidably mounted on the awl bar for making incisions in the work during the insertion of fastenings therein, yielding means normally 65 urging the incising means away from the work, and means for positively operating the incising means toward the work.

22. In a machine of the class described, 70 the combination of an awl arranged to penetrate and feed the stock, and a cutter operable to make an incision in the stock in predetermined relation to the point at which it is penetrated by the awl.

23. In a machine of the class described, 75 the combination of a driver for inserting fastenings in shoe stock, an awl for feeding the stock between successive fastening inserting movements of the driver, and a cutter operable to cut the stock in predetermined relation to the points at which the fastenings 80 are inserted.

24. In a machine of the class described, 85 the combination of an awl, operating means for the awl arranged to cause the awl to penetrate and feed the stock, and a cutter operable to make incisions in the stock substantially perpendicular to the surface thereof and in predetermined relation to the points at which the stock is penetrated 90 by the awl.

25. That improvement in the manufacture of shoes which comprises forming holes in the shoe stock to receive fastenings, utilizing the holes to feed the stock, and 95 cutting the stock in predetermined relation to certain of said holes.

26. That improvement in the manufacture 100 of shoes which comprises making one or more cuts in the edge portion of one of a plurality of parts of a shoe, forming a plurality of holes in predetermined relation to said cut or cuts for the reception of fastening means to secure together the parts, and utilizing the holes to feed the 105 work between the making of successive cuts.

In testimony whereof we have signed our names to this specification.

GEORGE GODDU.

FRED LUTHER MACKENZIE.
